7 Claims. (Cl. 315—40)

1

The present invention concerns an electron tube for ultra-short electromagnetic oscillations which has at least one cathode, an anode consisting of segments biased positively with respect to the cathode, and a magnet field, there being a high frequency alternating voltage between neighbouring anode segments, and where at a distance which is approximately constant from the anode a guide electrode is provided which at least over its greatest part is not penetrated by the electrons, the electrodes following paths between the guide electrode and the anode.

The high frequency alternating field of the electron tubes produces for instance by means of induction or influence effect high frequency currents in the tube elements, such as the cathode, the guide electrode, and the like, and this results in a loss of high frequency power. The losses can be of an ohmic nature, or on the other hand these may be caused by the radiation of high frequency energy.

The object of the present invention is to avoid these disadvantages. This is achieved by connecting part of the tube, which does not belong to the oscillating circuit for determining the frequency of the tube and in which high frequency currents occur during operation, to a low-radiation electrical oscillating system which is tuned in such a manner that the high frequency losses of the tube are at least approximately a minimum.

A number of constructional examples of the invention are illustrated diagrammatically in the accompanying drawing where Fig. 1 shows a sectional view of a tube, Fig. 2a is a circuit diagram of a cathode heating circuit embodying the invention; Fig. 2b is a fragmentary central section illustrating a constructional form of a loss-reducing oscillating system connected to the heating circuit system, whilst Fig. 3 illustrates an arrangement of the oscillating system which serves simultaneously for collecting the high frequency energy.

In the sectional view of the tube shown in Fig. 1 the section is taken along a plane passing through the axis of the tube. Reference numeral 1 indicates the electron-emitting hot cathode which in this case is in the form of a spiral, 2 is a cylindrical guide electrode, and 11 a ring-shaped cavity resonator of rectangular section which is at anode potential. The capacitive part of the cavity resonator is mainly formed by the segments 5 which are arranged next to each other in the circumferential direction. 8 is a conductive loop for collecting the energy. The

method of operation of the tube has already been described in detail in my copending application Ser. No. 583,220, filed March 17, 1945, and now U. S. Patent No. 2,508,280, issued May 16, 1950, so that it does not need to be repeated again.

The leads 12 for the heating current are in the form of Lecher lines which are closed by a capacitance 13. The Lecher line can be varied for instance by shifting the capacitance 13 together with its leads 14 along the Lecher system 12. The oscillating circuit comprising the Lecher system 12, the capacitance 13 with the leads 14, and the cathode 1, is tuned according to the invention in such a manner that the high frequency losses are a minimum. Tuning is not necessarily achieved by varying the electrically effective length of the Lecher line. It can also be varied by altering the capacitance of the condenser 13.

20 The side plates 7 of the electron tube are connected to a further Lecher system; this system is tuned by shifting the short-circuiting element 16 to such an extent that a value is reached where the high frequency losses are a minimum. 25 Tuning for minimum high frequency losses of the tube is generally achieved when the length of the Lecher line is an uneven multiple of a quarter wave length of the prevailing oscillations, preferably equal to $\lambda/4$.

30 In the constructional example shown in Fig. 1 the guide electrode 2 is conductively connected to one of the side plates 7. If this is not the case with other constructional forms of the tube, it is advisable to connect guide electrode and side plates with separate individually tuneable oscillating systems. Furthermore it is generally an advantage if the high frequency oscillation circuits are mutually decoupled. Such decoupling is not only advisable between the oscillation circuits in order to reduce the high frequency losses, but also between the latter and for instance the collector loop 8. With Lecher lines it is possible to achieve such a decoupling effect by arranging them perpendicular to each other.

45 With the form of the invention shown in Figs. 2a and 2b the detrimental radiation at one end of the line is prevented by a screening pot 16 instead of a tuned two-wire Lecher line. Reference numeral 1 indicates the hot cathode and 12 are the cathode leads. Screening pot 16 has a length of $\lambda/4$ or an uneven multiple of same. The screening pot can be located inside or outside the tube vessel. Since there is a magnetic field in a direction parallel to the cathode, with 50 55 a special constructional form of the tube having

a permanent magnet M, the screening pot is combined with the magnet in such a manner that the external conductor is at least partly formed by the iron of the magnet and is constructed as a bore in the iron of the magnet. A cathode lead 12 extends through the bore of magnet M, and a conductive plug 16a is slidable in the bore and on the lead 12 to adjust the effective length of the screening pot.

Since the cathode is surrounded by the magnetic lines of forces of the high frequency oscillations of the cavity resonator, these induce electric currents in the cathode which due to the tuning of the heating conductors are prevented from flowing away over the heating current source. Appreciable wattless currents therefore flow in the oscillating circuit which blocks the high frequency. With the constructional form according to Fig. 3 these currents are used for collecting the high frequency energy. In this figure there is a cavity resonator 11 and a cathode 1 with the current leads 12. Tuning is achieved by means of the impedance 17, an element which has capacitive and/or inductive properties. In this form of the invention a low-loss conductor 18 is arranged in parallel with the heating spiral, so that the oscillating system is as far as possible free from losses. To prevent the heating current from flowing through this conductor, one end of this latter is connected over a capacitance 19 to the oscillation circuit for reducing the high frequency losses, so that there is a separation of the direct-current kind. Collector electrode 20 serves to collect the high frequency energy.

As a result of coupling the cavity resonator oscillations with the currents flowing in the oscillation circuits, the frequency of the oscillations of the cavity resonator can be influenced by varying the tuning of the oscillation circuits. It is therefore advisable to make the impedance 17 variable. In a modified form of the Fig. 3 circuit the impedance 17 consists of a cavity resonator.

Another modified constructional form of the invention is obtained by substituting a tube arrangement, not shown, which acts as a variable condenser, for the capacitance 13 of Fig. 1, this tube being influenced for instance by altering the grid bias. This enables the tube oscillations to be modulated.

Other embodiments of the invention in which the cathode is electrically connected between and mechanically supported by a pair of side plates are described and claimed specifically in my copending application Ser. No. 696,117, filed September 11, 1940, which matured as Patent No. 2,522,184 on September 12, 1950.

I claim:

1. An electron tube for generating ultra short electromagnetic oscillations comprising an evacuated envelope, a cathode and an anode within said evacuated envelope, said anode consisting of segments adapted to be biased positively with respect to said cathode and arranged in a cylindrical array defining a cylindrical space within which said cathode is located, means for establishing a magnetic field within said cylindrical space and parallel to the axis thereof, a guide electrode of generally cylindrical form within said cylindrical space and located at a substantially uniform distance from said anode seg-

ments, whereby electrons emitted by said cathode follow cycloidal paths in the annular space between the anode segments and said guide electrode, and a tuned oscillation system connected to said guide electrode; said oscillation system being non-resonant at the frequency of the generated oscillations.

2. An electron tube as recited in claim 1, wherein said cathode is provided with leads for connecting the same in a cathode-heating circuit, in combination with means suppressing currents of the frequency of the generated oscillations in said cathode and cathode leads, said suppressing means comprising a screening pot on one cathode lead and having a length equal to a quarter-wavelength of the generated oscillations.

3. An electron tube as recited in claim 2, wherein said means for establishing a magnetic field comprises a permanent magnet having bores therethrough in axial alignment with said cathode, said cathode leads extend from opposite ends of said cathode and pass through said bores, and said screening pot comprises a conductive plug slidable in one of said bores and on the cathode lead extending through that bore.

4. An electron tube for generating ultra short electromagnetic oscillations comprising an evacuated envelope, a cathode and an anode within said evacuated envelope, said anode consisting of segments adapted to be biased positively with respect to said cathode and arranged in a cylindrical array defining a cylindrical space within which said cathode is located, means for establishing a magnetic field within said cylindrical space and parallel to the axis thereof, side plates insulated from said anode segments and arranged perpendicular to the axis of said cylindrical space at the ends thereof, and a tuned oscillation system connected to said side plates; said oscillation system being non-resonant at the frequency of the generated oscillations.

5. An electron tube as recited in claim 4, in combination with a guide electrode of generally cylindrical form within said cylindrical space and located at a substantially uniform distance from said anode segments, said guide electrode being mechanically and electrically connected to one of said side plates.

6. An electron tube as recited in claim 4, wherein at least a part of said tuned oscillation system is a Lecher line.

7. An electron tube as recited in claim 6, wherein said Lecher line includes means adjustable to vary the electrically effective length thereof.
